(57) **CLAIM**

The ornamental design for a splash shield, as shown and
described.

DESCRIPTION

FIG. 1 is a perspective view of a splash shield illustrating a
new design.

FIG. 2 is a front elevation view of the splash shield shown in FIG. 1.

FIG. 3 is a rear elevation view of the splash shield shown in FIG. 1.

FIG. 4 is a left-side elevation view of the splash shield shown in FIG. 1.

FIG. 5 is a right-side elevation view of the splash shield shown in FIG. 1.

FIG. 6 is a top view of the splash shield shown in FIG. 1.

FIG. 7 is a bottom view of the splash shield shown in FIG. 1.

Shade lines shown in the accompanying drawings of FIGS. 1-7 represent surface contour only and not texture, color shading, or surface ornamentation.

FIG. 8 is a perspective view of a splash shield illustrating a new design.

FIG. 9 is a front elevation view of the splash shield shown in FIG. 8.

FIG. 10 is a rear elevation view of the splash shield shown in FIG. 8.

FIG. 11 is a left-side elevation view of the splash shield shown in FIG. 8.

FIG. 12 is a right-side elevation view of the splash shield shown in FIG. 8.

FIG. 13 is a top view of the splash shield shown in FIG. 8.

FIG. 14 is a bottom view of the splash shield shown in FIG. 8.

Shade lines shown in the accompanying drawings of FIGS. 8-14 represent surface contour only and not texture, color shading, or surface ornamentation. Broken lines shown in the accompanying drawings of FIGS. 8-14 represent structure that is not part of the claimed design, but rather illustrate the environment in which the design is used.

FIG. 15 is a perspective view of a splash shield illustrating a new design.

FIG. 16 is a front elevation view of the splash shield shown in FIG. 15.

FIG. 17 is a rear elevation view of the splash shield shown in FIG. 15.

FIG. 18 is a left-side elevation view of the splash shield shown in FIG. 15.

FIG. 19 is a right-side elevation view of the splash shield shown in FIG. 15.

(Continued)

FIG. 20 is a top view of the splash shield shown in FIG. 15. FIG. 21 is a bottom view of the splash shield shown in FIG. 15.

Shade lines shown in the accompanying drawings of FIGS. 15-21 represent surface contour only and not texture, color shading, or surface ornamentation.

FIG. 22 is a perspective view of a splash shield illustrating a new design.

FIG. 23 is a front elevation view of the splash shield shown in FIG. 22.

FIG. 24 is a rear elevation view of the splash shield shown in FIG. 22.

FIG. 25 is a left-side elevation view of the splash shield shown in FIG. 22.

FIG. 26 is a right-side elevation view of the splash shield shown in FIG. 22.

FIG. 27 is a top view of the splash shield shown in FIG. 22; and,

FIG. 28 is a bottom view of the splash shield shown in FIG. 22.

Shade lines shown in the accompanying drawings of FIGS. 22-28 represent surface contour only and not texture, color shading, or surface ornamentation. Broken lines shown in the accompanying drawings of FIGS. 22-28 represent structure that is not part of the claimed design, but rather illustrate the environment in which the design is used.

The broken away symbols in the drawings indicate that any portion of the article beyond what is shown forms no part of the claimed design.

1 Claim, 20 Drawing Sheets

Related U.S. Application Data

a continuation of application No. 29/717,370, filed on Dec. 17, 2019, now Pat. No. Des. 961,055.
